(57) CLAIM

I claim the ornamental design for a drinking straw, as shown and described.

DESCRIPTION

FIG. 1 is a front elevation view of a drinking straw showing my new design;

FIG. 2 is a left side perspective view thereof, the opposite side being a mirror image; and,

FIG. 3 is a rear elevation view thereof.

1 Claim, 3 Drawing Sheets

FIG. 1

FIG. 2

FIG. 3
